UNITED STATES PATENT OFFICE

ERNEST J. HORTON, OF PITTSBURGH, PENNSYLVANIA, ASSIGNOR TO RUUD MANUFACTURING COMPANY, A CORPORATION OF NEW JERSEY

AUTOMATIC CUT-OFF VALVE

Application filed February 17, 1932. Serial No. 593,469.

This invention relates to valves, and more particularly to automatic cut-off valves, such as are adapted for use with fuels either in gas or liquid form.

5 An object of this invention is the provision of an automatic cut-off valve arrangement, such as may be applied to main and auxiliary burners, (for example, a main burner and a pilot burner) that shall be simple in construction, easily manufactured, efficient and positive in operation.

Another object of the invention is the provision of an automatic cut-off valve arrangement for controlling a main burner and an auxiliary burner, whereby upon the opening of a valve controlling the auxiliary burner and the lighting thereof, another valve controlling the main burner is automatically opened and thereafter both valves placed 20 under automatic control so that upon failure of the fuel supply or upon the extinguishment of the pilot burner, or both, for any reason, both valves will be closed automatically.

25 A further object of the invention is the provision of a multiple valve control whereby one valve may be manually opened and latched in such position, and subsequently another valve opened by means of a thermostatic device, the construction of the multiple valve control being such that when the thermostatic device has operated, all of the valves are placed under the control thereof.

Other objects of the invention will, in part, 35 be apparent and will, in part, be obvious from the following description taken in conjunction with the accompanying drawing in which;

40 Figure 1 is a view partially in section and partially in side elevation of an automatic cut-off valve, as applied to a pilot or auxiliary burner and a main burner, the latter being illustrated by dot and dash lines;

45 Fig. 2 is an end view of the cut-off valve; Fig. 3 is a view in section of a portion of the valve shown in Figs. 1 and 2 taken on lines III—III thereof; and

50 Figs. 4 and 5 are views in front and side elevation, respectively, of a valve actuating

and latching device embodied in the valve shown in Figs. 1 and 2.

Throughout the drawing and the specification like reference characters indicate like parts.

55 In Fig. 1 of the drawing, a main burner 1 is shown to which fuel, such as gas, is supplied from a supply line 2. The particular type of burner illustrated, is designed to operate either in the so-called automatic hot water heaters in which the supply of gas is turned on and off at the main burner automatically as the flow of water from such heaters is turned on and off in accordance with the demand for hot water; or in the storage 60 type of heater where the gas to the main burner is turned on and off in accordance with the temperature of the water therein.

65 In order that the gas delivered to burner 1, each time water is drawn from the heater, 70 may be ignited the usual pilot light or auxiliary burner 3 is provided. Burner 3 is mounted on the main burner as shown and is supplied with fuel or gas from an auxiliary 75 or branch line 5 which, it will be understood is connected to the main fuel supply line at a point ahead of the valve mechanism (not shown) which turns on or shuts off the gas to the main burner in accordance with the demand for hot water, or in accordance with 80 water temperature.

85 Under normal conditions, the pilot or auxiliary burner 3 is burning at all times. Occasionally, however, unexpected conditions arise which cause the flame at the pilot or auxiliary burner to be extinguished. In such a case, gas would escape through the main burner, as well as the auxiliary burner or pilot light, unless provision were made to automatically and positively shut off the gas supply thereto until the pilot light or auxiliary burner has been relighted.

90 In order to permit gas to flow to main burner 1 and pilot burner 3 so long as the pilot burner is burning, and to provide for 95 positively shutting off the flow of gas thereto in case the pilot or auxiliary burner is extinguished, a multiple valve 6 and a thermostatic device 7 are provided. The multiple valve controls the flow of gas to burners

1 and 3 and is under the control of the thermostatic device.

Multiple valve 6 comprises a valve body 8 having a port 9 therein which is controlled by a valve 10 preferably of the poppet type. The valve body is provided with an inlet 11 which is connected to the main supply line 2 and an outlet 12 which is connected to the mixing chamber 13 of the main burner 1, the 10 port 9 being interposed between the inlet and outlet of the valve body. Poppet valve 10, as shown, is normally urged towards its closed position by means of a coil spring 14.

Valve body 8 carries a bonnet or cap 15 which serves as the body for the valve which is utilized to control the flow of gas to pilot or auxiliary burner 3. As shown, the cap or bonnet has a flange 16 adapted to seat on the valve body. In order to provide a gas-tight joint between valve body 8 and cap or bonnet 15, a washer or gasket 17 of suitable form and composition is interposed therebetween. The bonnet or cap may be positively and rigidly secured to valve body 8 by means of screws 18 (see Fig. 2). Bonnet or cap 15 is provided with an inlet port 20 to which branch line 5 is connected, and an outlet port 21 which is connected directly to the pilot light as shown. To provide for the 30 flow of gas from the inlet port 20 to the outlet port 21, passageways 22 and 23 are drilled in the body 15 so as to provide communication with the interior bore thereof. As shown, a seat 24 is formed in bonnet or cap 35 15 which is interposed between the passages 22 and 23 so that the flow of gas therethrough may be closed or shut off by means of a valve 25. Valve 25, as shown, is of cup shape, open at one end and closed at the other. The 40 closed end is shaped to conform to the seat 24 so that when the valve is seated the flow of gas will be positively shut off.

Valve 25 includes a plug 26 and a stem 27, the stem extending through the plug. The 45 plug is threaded into the cup shaped member, as shown, and when in place clamps a head 28 of the stem between the bottom of the cup shaped member and the adjacent end of the plug 26.

The valve bonnet or cap 15 is threaded at its upper end to receive a plug 29 which is drilled to accommodate the stem 27. The 50 plug 29 is provided with a gland 30 in which packing may be disposed, the packing being retained in its proper position by means of a gland nut 31 which is threaded into the plug.

In order that valve 25 may be urged towards its closed position, a compression 60 spring 32 disposed about the valve stem 27 and between valve 25 and plug 29, is provided. To provide for manually opening valve 25, so that gas may be delivered to the pilot light, when it is desired to light the same, means are provided for raising the 65 valve off its seat and latching the same in its

open position. The means illustrated comprises a member 33 having a slot 34 therein through which valve stem 27 extends. As shown, the upper portion of member 33 is relatively thin and the lower portion relatively thick, the thin and thick portions being connected by an inclined surface 35 which acts as a wedge. The lower end of the member 33, as viewed in Fig. 1, is provided with a knob that serves as a thumbhold for convenience in opening valve 25. As shown in Fig. 1, the outer end of stem 27 is provided with a nut 36 having an annular flange 37 disposed adjacent to the working surface of member 33.

When member 33 is moved upwardly, as viewed from Fig. 1, the inclined surface 35 on member 33 acting as a wedge, moves stem 27 outwardly, that is to the right as viewed from Fig. 1, and raises the valve 25 from its seat. When member 33 is pushed upwardly as far as it will go, the flanged nut 36 rests on surface 38 thereof. Since coil spring 32 is urging valve 25 towards its closed position, there will be sufficient friction between the 90 flanged nut 36 and member 33 to hold the latter in the position in which the valve will be held open. The gas or fuel is now flowing to the pilot burner 3 so that it may be lighted.

When the pilot burner has been burning for a predetermined length of time, thermostatic device 7, which is responsive to the heat developed by the flame of the pilot burner, comes into action and opens the poppet valve 10 which controls the flow of gas to the main burner 1. As will be explained subsequently herein, means are provided whereby when poppet valve 10 has opened a predetermined distance, poppet valve 25 controlling the flow of gas to the pilot burner 1 will be opened still further so that member 33 will be released to the position shown in Figure 1. When member 33 has fallen to the position shown in Fig. 1, valves 10 and 25 are both under the control of thermostatic device 7 so that, in case the pilot burner is extinguished, or the fuel supply fails for some reason or other, both valves will be positively closed, thereby preventing the escape of gas from the 115 burners. It is, therefore, necessary in case the pilot burner goes out to repeat the above described operations before the pilot burner can be relighted.

Thermostatic device 7 comprises a curved bimetallic strip 40 which is disposed in the path of the plane of the pilot burner. As shown, the bimetallic strip is anchored at one end to a support 41 which is threaded on one end of a tubular member 42. Tubular member 42 is threaded into a boss 43 formed as an integral part of valve body 8. The free end of the bimetallic strip 40 is operatively connected to a rod 44 which is disposed within the tubular member 42. The other end of the 130

rod engages the poppet valve 10. When the thermostatic or bimetallic member has been heated to a predetermined temperature, the free end thereof deflects to the right, as viewed from Fig. 1, thereby pushing rod 44 to the right and lifting valve 10 off its seat so that gas may flow through port 9 to burner 1.

In order to provide for certain adjustments in the action of the thermostatic device, nuts 45 are threaded on the end of the rod engaged by the bimetallic member 40. The bimetallic member may bear on a cone-shaped member 46. Thus by turning the nuts 45 towards the end of the rod or towards the support 41, the temperature at which the bimetallic member becomes effective to open valve 10 may be adjusted or regulated to some predetermined value.

In order to maintain rod 44 in alignment within the tubular member 42 and also to provide a means for sealing off the flow of gas from valve body 8 into the tubular member, a bushing 47 is provided. The bushing 25 embraces rod 44 and is disposed within the end of the tubular member 42 that engages the valve body. Packing of any suitable form or composition may be disposed at the end of the tubular member, a pocket or cavity 30 48 being provided in boss 43 for this purpose. To further provide against leakage of gas from the valve body into the tubular member, rod 44 is provided with a plurality of grooves 49 which are adapted to contain lubricant of 35 suitable texture. The lubricant contained in these grooves acts as a seal against the flow of gas along the rod.

Poppet valve 10 comprises a body portion 51 having a flanged rim 52 for receiving a disc 53 of leather or other suitable material. Disc 53 seats on the valve seat of the valve body to close the port 9, when the valve is in the position shown in Figure 1. The disc 53 may be held in place by means of a washer 45 54 which is clamped in position by means of a threaded bushing 55 threaded into the body 51. As shown in the drawing, the end of rod 44 that engages body 51 of valve 10 is tapered to a point so that positive engagement between the end of the rod and the end 50 of the valve may be assured.

In order that member 33 may be released to the position shown in Fig. 1, when valve 10 is opened, so that both valves 10 and 25 may be placed under the control of the thermostatic device 7, valve 25 is provided with a stem 56 which extends through the base of the bonnet or cap 15 and terminates short of the valve body 51 of poppet valve 10. The portion of the bonnet or cap 15 extending into valve body 8 is tapped to accommodate a stuffing nut 57 through which stem 56 passes.

Stuffing is interposed between nut 57 and the 60 tapped cavity in bonnet or cap 15 to prevent

the flow of gas from the valve body into the bonnet or cap.

When the pilot light has been burning for a predetermined length of time, as stated previously herein, the bimetallic member 40 deflects to the right as viewed from Fig. 1 moving the rod 44 to the right and opening valve 10. Further travel of rod 44 causes body 51 of valve 10 to engage the end of stem 56 and move valve 25 to the right until member 75 33 is released to the position shown in full lines in Fig. 1. Valves 10 and 25 are now under the control of the bimetallic member so that in case the pilot flame goes out both valves will be closed by the springs associated therewith when the bimetallic member has cooled and assumed the position indicated in Fig. 1.

To relight the pilot light, member 33 is pushed upwardly to the position indicated 85 in broken lines in which its position is held between the flanged nut 36 and the stuffing nut 31. Member 33 thus acts as a latch to hold the pilot valve open so that it is not necessary for the operator to manually hold 90 the pilot valve open until the main burner valve has been opened by the bimetallic member. Thus the multiple valve embodies a manually operable valve which may be manually opened and held in its open position by 95 means of a latch, and a main burner valve which is actuated by a thermostatic device energized by the heat developed by the pilot burner. The arrangement of the valve and the thermostatic device is such that when 100 the main burner valve has been opened to a predetermined position, the manually operable pilot valve is unlatched (that is, the latch is released to that position in which the valve may be returned to its closed position when the main burner valve is closed), 105 whereby both valves are placed under thermostatic control, that is, under the control of thermostatic device 7.

It will be apparent, that by the form of 110 construction of the valve, the pilot light may be lighted before the gas or fuel is turned on to the main burner, thus avoiding possible danger of explosions which might occur should the gas be turned on to the main 115 burner at the same time that it is turned on to the pilot burner.

Thus the pilot burner valve may be actuated to its open position independently of the main burner valve and it may be held in such open position by a mechanical latch which is automatically tripped free of the pilot valve the moment that the main burner valve has opened to a predetermined position. 120

While various modifications and changes may be made in the device herein disclosed without departing from the spirit or the scope of the invention, it is to be understood 125 that only such limitations shall be placed 130

on the invention as are imposed by the prior art and the appended claims.

What I claim as new and desire to secure by Letters Patent is:

- 5 1. In combination with a pilot burner and a main burner, of a valve disposed to control the flow of fuel to the pilot burner, a valve disposed to control the flow of fuel to the main burner, means for manually opening said pilot burner valve and holding said valve open, and means responsive to the heat developed by said pilot burner for opening said main burner valve and releasing said pilot valve holding means to a position in which said valve may close upon the extinguishment of the pilot burner.
- 10 2. In combination with a pilot burner and a main burner, of a valve disposed to control the flow of fuel to the pilot burner, a valve disposed to control the flow of fuel to the main burner, means for manually opening said pilot burner valve and holding the same open, and means responsive to the heat developed by said pilot burner for opening the main burner valve, releasing the pilot burner valve holding means and holding both of said valves open while the pilot burner is burning, said heat responsive means being arranged to close both of said valves in response to the extinguishment of said pilot burner.
- 15 3. The combination with a source of supply of fuel, a pilot burner and a main burner, of a valve disposed to control the flow of fuel to the main burner, a valve disposed to control the flow of gas from said source to said pilot burner, means for manually opening said pilot burner valve including a latch for holding said valve open, and means responsive to the heat developed by said pilot burner for opening said main burner, releasing said latch and placing both of said valves under the control of said heat responsive means.
- 20 4. In combination, a pilot burner, a main burner, a valve for controlling the flow of fuel from a source of supply to the pilot burner, a valve for controlling the flow of fuel from said source to the main burner, means for holding said pilot valve open, and means responsive to the heat developed by the pilot burner for opening said main burner valve, said heat responsive means, after the main burner valve has been opened, being operable to cause both valves to close in case the flame at the pilot burner becomes extinguished.
- 25 5. In combination, a pilot burner, a main burner, a valve for controlling the flow of fuel from a source of supply to the pilot burner, a valve for controlling the flow of fuel from said source to the main burner, means for holding said pilot valve open, means responsive to the heat developed by the pilot burner for opening said main burn-

er valve, and means coacting with said main burner and pilot burner valves arranged to release said holding means and place both of said valves under the control of said heat responsive means.

6. The combination with a pilot burner, a main burner, and a source of supply of fuel for said burner, of a valve for controlling the flow of fuel to said pilot burner, a valve for controlling the flow of fuel to said main burner, means for partially opening said pilot burner valve and holding the same in said partially open position, means responsive to the heat developed by said pilot burner for opening said main burner valve and a connection between said valves arranged to increase the opening of said pilot burner valve in response to the opening of said main burner valve for releasing said pilot valve holding means and placing both of said valves under the control of said heat responsive means.

In testimony whereof, I have hereunto subscribed my name this 16th day of February, 1932.

ERNEST J. HORTON.
